UNITED STATES PATENT OFFICE.

EUGENE SONNTAG, JR., OF ASTORIA, NEW YORK, ASSIGNOR TO M. LOWENSTEIN & SONS, INC., OF NEW YORK, N. Y., A CORPORATION OF NEW YORK.

DESIGN FOR A TEXTILE FABRIC.

Application filed December 2, 1922. Serial No. 4,467. Term of patent 3½ years.

To all whom it may concern:

Be it known that I, EUGENE SONNTAG, Jr., a citizen of the United States, and a resident of Astoria, Long Island, in the county of Queens and State of New York, United States of America, have invented a new, original, and ornamental Design for Textile Fabric, of which the following is a specification, reference being had to the accompanying drawings, forming part thereof, in which the figure shows one complete repeat of the design applied to a piece of textile fabric.

I claim:

The ornamental design for a textile fabric, as shown.

EUGENE SONNTAG, JR.
